MACHINE AND METHOD FOR SETTING ELEMENTS UPON A STRIP

Ernest Hopkinson, New York, N. Y., and Frank A. Belanger, Fred A. Aleott, and Edwin F. Hewitt, Waterbury, Conn., assignors, by mesne assignments, to United States Rubber Company, New York, N. Y., a corporation of New Jersey

Application June 24, 1931, Serial No. 546,506

24 Claims. (Cl. 153—1)

This invention relates to the art of separable quick operating fastening devices of the type wherein a slider associated with a series of coacting fastener elements disposed along the sides 5 of an opening may be actuated therealong in order to open or close the opening by disengaging or interlocking said elements. The invention is particularly directed to an apparatus for setting or affixing such fastener elements to a cored carrying strip which may be sewn or otherwise connected to the sides of the opening desired to be opened and closed. The fastener elements contemplated are metal elements having separated legs for clamping upon carrying strips disposed on opposite sides of the opening, each element having a head or contact portion provided with a recess on one side and a protuberance on the other, the respective heads and protuberances of cooperating elements on opposite sides of the opening being arranged so that the elements may alternately interlock with each other. The invention is particularly applicable therefore to setting or affixing fastening elements of the type disclosed in the patent to Willard H. Cobb, No. 1,761,385, patented June 25, 1930.

An object of this invention is to provide an apparatus whereby fastener elements with separated legs may be continuously applied to and clamped in position upon a carrying strip.

Another object is to make it possible to set fastener elements on a carrying strip with greater precision than has heretofore been possible.

Another object is to provide an apparatus by means of which fastener elements may be handled readily and efficiently and applied to and set upon a carrying strip with rapidity.

A further object is to enable strips with fastener elements positioned thereupon, hereinafter referred to as "stringers", to be continuously made in a desired length with a predetermined space between lengths.

Other objects and advantages of the invention will more clearly appear when reference is had to the following specification and drawings:

The invention broadly comprises means for feeding legged fastener elements head first into an advancing chain constructed with holding recesses in which the heads may be seated and held, means for advancing the chain around a

wheel and thus reversing the position of the elements so their legs are downwardly extending and thus feeding said elements longitudinally of a carrying strip with the legs straddling the cored edge of the same, and means for affixing the elements to said strip by closing or clamping the legs over the cored edge thereof while the elements and strip are continuously advancing.

With the objects of the invention together with the broad means for its accomplishment set out above, in mind, a detailed description of the apparatus will be proceeded with.

Fig. 20 is an end view of the device of Fig. 19.

Fig. 21 is an end view of a tape or strip positioning mechanism which may be used with the apparatus, this mechanism being omitted from Figs. 19 and 20, but being shown in position adjacent the end of the tape or strip guiding and tensioning mechanism in Fig. 2.

Fig. 22 is a fragmentary side view of part of the ratchet mechanism which automatically suspends the flow of fasteners at predetermined 20 times to allow stringers of predetermined length to be made.

Fig. 23 is a perspective view of a trip mechanism for throwing out the main clutch of the apparatus in the event a fastener element becomes caught between moving parts or in the event the strip or tape becomes accidentally caught upon some part of the machine.

Fig. 24 is a section along line 24-24 of Fig. 1 showing the construction of the main clutch.

Fig. 25 is a fragmentary view along line 25-25 of Fig. 3 showing the clutch operating lever and the manner in which it is actuated by the automatic trip mechanism.

Before proceeding to a detailed explanation of the machine, the operation will be briefly described. Referring to Figs. 9 and 11, fastener elements 29 are fed head first down the chute 30 into chain 31. The elements are lodged in the chain as shown in Fig. 10 and the chain advanced 40 around wheels 32 and 33 in order to feed the elements longitudinally of the carrying strip 35 which passes through slot 131 with the legs of the elements straddling the corded edge 36 of the strip. While so moving the legs of the elements 45 are clamped upon the corded edge by hammers 34 in the manner shown in Figs. 16 and 17 which are cross sectional views taken at right angles to the chain and associated mechanism. The strip is moved continuously forward by the pull exerted 50 by elements already clamped in position thereon and whose heads are still carried forward by the chain. The finished stringers may be seen leaving the machine at the left of Fig. 2.

The construction of the apparatus may be seen 55 by referring to Fig. 1, showing a suitable base plate 1 which may be mounted in a frame provided with uprights 2 which carry bearings 3 arranged to journal a driving shaft 4. This shaft is provided with a crank 5 to which is connected 60 connecting rod 6 carrying cross head 7 for reciprocation vertically in guides 8. Fly wheel 9, mounted for free rotation about the shaft 4, may be driven by suitable means, for instance by running a belt thereover. A clutch may be provided 65 in the form of a collar 10 fixed to the shaft 4 and provided with operating keys 11 slidable in keyways 12 (see Figs. 1 and 24). A lever 13 is pivoted at 14 and the frame of the machine so that it may be actuated by rod 15 in order to position the cam faces 16 of the lever 13 in the path of coacting faces 17 on the operating keys and thus push the same inwardly and out of the path of pin 18 affixed to the fly wheel 9 thereby disengaging the clutch. The keys 11 are urged outwardly by springs 19 seated in recesses in the

enlarged part of collar 10. Spring 20 operating against pin 21 is arranged in the frame of the machine to tend to push lever 13 upwardly against its own weight and spring 23 operating between the machine frame and collar 24 is provided to urge rod 15 upwardly. The rod 15 extends downwardly underneath the machine and is pivotally connected to the treadle bar 25 whose other end is fixed to the upright operating lever 26 as at 27 (Figs. 3 and 25). The treadle bar is 5 pivoted on the frame of the machine as at 28. The action of the operating lever 26 through bar 25 and rod 15 will be specifically described hereinafter.

The element carrying chain is actuated by 15 shaft 40 which carries sprockets 41 for meshing into the driving links 42 of the chain 31 (Figs. 1 and 9). The rotation of the shaft 4 is transferred through bevel gears 43 and 44 to shaft 45 at the lower end of which is a bevel 46 meshing 20 with another bevel 47. This latter gear revolves loosely upon shaft 40 but is connected thereto by a clutch 48 which consists of a toothed clutch face 49 keyed to shaft 40 for slidable movement thereon and urged by spring 51 (Fig. 3) into 25 intermeshing relation with a complementary face 50 integral with gear 47. The spring 51 is seated against the collar 52 on the end of the shaft 40. Clutch member 49 has an enlarged collar portion 53 arranged between rollers 54 disposed on an 30 arm 55 which operates the tripping mechanism for throwing out the main clutch. This operation will be later described.

Rotation of the sprockets 41 (one on each side of the chain) causes the chain to be advanced 35 around flanged wheels 32 and 33 (see Figs. 9 and 12) on shafts 83 and 84 journaled in side pieces 74 and 74' and 75 and 75'. These wheels contact with the inner portions of the fastener elements carrying members 85 of the chain. These 40 members consist of L-shaped links provided with upstanding portions 86 which are recessed at 87 adapted to receive or seat the humps of the elements 29. The L-shaped links are provided with bearing recesses through which link pins 88 are 45 extended to hold the links together and to the driving links 42 which are provided on each side in staggered relation. This construction is shown clearly in Figs. 10 and 10A. Support 82, in the form of a plate, extends between the flights of 50 the chain and prevents it from weaving, as shown in Fig. 9.

As the chain passes over wheel 32 at the back of the machine, the upstanding portions 86 fan out as in Figs. 9 and 11 and allow fastener elements 29 which are fed down chute 30 to seat themselves therebetween with their legs outwardly extending. In this position they are carried around the wheel 32 until their legs pass out of contact with guide 73 and rest adjacent 60 plates 154 and 155 (Fig. 16) with their crotches on the corded edge 36 of the tape 35 which is moved along with the elements at the same speed as that of the chain. During this movement hammers 34 are driven inwardly thereby clamping the legs of the fastener elements on the carrying strip as shown in Fig. 17. The chain carries the clamped elements forward and thus provides a means for feeding the carrying strip at a proper rate of speed. The operation of the hammer mechanism will now be described.

Fixed to cross head 7 are cam arms 101 provided with foot portions 102 which latter have rail-shaped toes 103 arranged to reciprocate up and down in guide tracks 104. Between the head 75

and foot portions 101 and 102 are slots 105 into which plates 106 bolted to slide blocks 107 are fitted for reciprocating the slide blocks in the direction of movement of the chain. The slide blocks are guided in this movement by flanges 108 on member 110 and flanges 109 connected with members 111, the members 110 and 111 being disposed in fixed relation to the base plate 1 (Fig. 12). The slide blocks may be provided with springs 127 (Fig. 3) acting against blocks 128 fixed to the base in order to take up lost motion.

Hammers 34 are arranged to slide back and forth transversely of the slide blocks 107 and are normally held away from contact with the fastener elements carried by the chain by means of spring 112 connected to pins 113 on the hammers and to pins 114 on the fixed members 126. The hammers are actuated by virtue of the reciprocating movement of the slide blocks which cause the cam surfaces 116 of the hammers to ride upon cam rollers 117 which are disposed in the path of the cam surfaces when the slide blocks 107 are moving in the same direction as the chain. Cam rollers 117 are mounted in members 111 and are disposed on rods 118 which extend upwardly through plates 126 and slide through frames 119 which are connected to the cross heads 7 at each side thereof. The rods are provided at this end with adjustable collars 120 in order to provide means for raising the shafts 118 at predetermined times when the crosshead ascends. Disposed over the cam rods 118 and fixed into frames 119 are adjustable pins 121. The lower parts of the rods 118 are journaled in members 111 and are provided with upper and lower annular grooves 122 adapted to seat balls 123 which are urged thereinto by springs 124 seated in fixed members 111. Plates 126 are bolted to members 111 and to the base 1 and limit the upward movement of the cam rollers, and provide bearings for the shafts 118.

In Figs. 1 and 2 the cross head is in its uppermost position and the hammers are pulled back into inoperative position as shown in Figs. 14 and 16. The last upward movement of the cross head raises the frames 119, the lower portions 100 of which catch collars 120 and raise rods 118 and cam rollers 117 to the position shown in Fig. 50 16 where the cam rollers are positioned inside the curved cam surface 115 of hammers 34 but without contact therewith sufficiently to force them inwardly. The cam rollers are retained in raised position by virtue of balls 123 being forced 55 into the lower set of grooves 122 by springs 124 (Figs. 16 and 12). As the cross head travels downwardly the cam arms 101 coat with the plates 106 sliding in grooves 105 and move the slide blocks 107 forward in the direction shown 60 by the arrows in Fig. 14. During this movement the hammers ride up upon the cam rollers 117, first on cam surface 116 and then on the ends of the hammers, at which position the hammers are forced inwardly to their maximum extent to 65 clamp the legs of the fastener elements over the corded edge 36 of the carrying strip 35 as shown in Figs. 15 and 17 and without interrupting the advancing movement of the strip 35. At the end of the downward movement the pins 121 butt against the ends of rods 118 and push the cam rollers 117 into the space 130 (Fig. 12) where they are locked by balls 123 being forced into the upper set of grooves 122 on rods 118 while the cam arms 101 pass the lowermost position and 70 move upward (moving slides 107 backward) until 75

the lower portions of the frames 119 again coat with collars 120 and pull the rods 118 upward in order to position the hammers for another clamping operation. During the upward travel of the crosshead and the rearward travel of the slide blocks, the hammers of course are not acted upon by rollers 117 and are retained in inoperative position by the springs 112. The operating cycle of the hammer mechanism begins again when the crosshead reaches its uppermost position. The hammers are preferably wide enough so that several fastener elements may be clamped on the carrying strip at one time, allowing sufficient time for the chain to position another group of elements while the hammers are withdrawn and being brought back for another clamping operation. The angle made by the cam arms 101 with the vertical and the speed of the chain may be varied in order to set a greater or less number of elements. 20

The carrying strip guiding mechanism (Figs. 19 and 20) consists of a plate 130 fixed to the base 1 and provided with a groove 131 through which the carrying strip is adapted to pass. The roller 143 on a shaft supported by block 144 25 may be provided in order that the corded edge of the carrying strip may be held down and the strip held in place in the groove 131. In order to extend the strip in a straight line longitudinally of the chain and at a slight but uniform tension while the fastener elements are being applied thereto, a metal presser strip 132 may be arranged inside the groove 131 so that it may be pushed against the strip by means of springs 133. The presser strip 132 is provided 30 with guide feet 134, the inner foot acting in a complementary groove in the supporting plate 130 and the outer foot being provided with a slot 135 through which a screw 136 may be inserted and threaded into plate 130. This construction 35 allows the presser strip to be yieldably forced against the side of the carrying strip or tape. Pin 137 provided with an easily accessible operating rod 129 secured to strip 132, is passed through a suitable hole in plate 130 so that the 40 strip 132 may be pulled back against the action of the springs 133 while a fastener element carrying strip is being initially threaded into the machine. 45

To the end 138 of the carrying strip guide 50 may be attached, by means of a bracket 153, a guiding mechanism such as that shown in Fig. 21, the same being shown in Fig. 2 in side elevation in the position it takes when attached to the machine. This consists of a block 139 55 having a slot 140 to accommodate tape. Pin 141, urged inwardly by a spring 142, is adjustably arranged in an opening in the block 139 at right angles to the tape slot. The pin is forced by the spring under the corded edge 36 of the carrier strip and forces the same to ride thereover in order to properly position the carrying strip or tape for passage through the machine. 60

In order to cut off the flow of fastener elements when the tape 35 runs out, a roller 145 65 is disposed at the end of one arm of a bell crank 146 so that it normally rests upon the corded edge of the tape as indicated in Fig. 2. The bell crank 146 is pivoted at 147 upon a support 148 attached to the plate 130. The other end 70 of the crank may be pivotally connected to link 149 which in turn is connected to another bell crank 150 pivoted at 151. The other end of the bell crank 150 is provided with an adjustable finger 152. When the tape 35 is exhausted from 75

its feeding reel or other means of supply (not shown) the roller 145 will drop down to the dot and dash line position of Fig. 2, thus moving the associated parts of the mechanism so that 5 finger 152 is depressed into the path of the fastener elements which are being fed down the chute 30, thus cutting off the supply and preventing fastener elements from being jammed between moving parts of the hammer mechanism.

10 After passing through the slot 131 in the guide plate 130, the carrying strip or tape passes between the plates 93 and 94 which rest upon member 110 and which are disposed adjacent the inside of member 74 which journal the shaft 15 of the chain roller 83. Immediately under the hammers 34 plates 93 and 94 are cut away and in their place are inserted adjusters 154 and 155 yieldingly held against the tape by springs 166 acting against pins 157 which are attached to the 20 adjusters (see Figs. 16 and 18). This construction holds the tape steady during the hammering operation yet allows for variation in width or imperfections or knots in the construction of the tape.

25 Means for positively feeding the elements into the chain and means for cutting off the feed at predetermined times in order to allow a proper dwell to produce spaces between predetermined lengths of stringers may be provided. Both these 30 means are arranged to operate from a cam wheel 160 disposed on the end of and rotating with the shaft 40. The rocker arm 161 is pivoted in a bracket at 162 and provided with a spring 163 which urges a contact surface or cam follower 159 into contact with the cam surfaces 164 on the cam wheel. At the other end of the rocker 161 is provided a pawl 165 (Fig. 22) urged by spring 166 against a ratchet 167 which rotates on a shaft 168 journalled in bracket 166 (Figs. 1 and 3). On the side of the ratchet gear 167 is provided a cam surface 170 adapted to coact against a surface 171 intermediate the ends of lever 172 as best shown in Fig. 3. One end of the lever 172 is pivoted upon the bracket at 40 173 and is urged inwardly toward the side face of the ratchet 167 by a spring 158 fixed to the ratchet carrying bracket. Another spring 174 exerts a braking action against the ratchet and prevents it from spinning upon impulses supplied through pawl 165. The other end of the lever 172 is terminated adjacent a pin 175 on link 176 (Fig. 11) which link is connected to a crank 177 which rotates the shaft 178 upon which is fixed a finger 179. As the cam wheel 160 is rotated, the rocker 161 is rocked between the action of the cam surface and springs 163 until the ratchet 167 is turned by pawl 165 to 45 push cam 170 against the coacting part of the lever 172. This latter is turned about its pivot 173 against the action of spring 158 while its outer end pushes the pin 175 to the left (when viewed as in Fig. 11) throwing out the feed mechanism (which will be later described) and rotating crank 177 and shaft 178 until the finger 179 50 assumes the full line position of Fig. 11, thus preventing fastener elements 29 from sliding down the chute 30. The cam 170 and the associated parts are arranged so that the cam will push against lever 172 for a predetermined interval in order to cause the finger 179 to be depressed for this same interval during the dwelling time between the application of successive stringer lengths. It can be seen that by adjusting the size of the parts and their relation with each other, stringer lengths of 55 60 65 70 75

sized sizes and at desired spacings may be made.

Means for insuring a positive feed of the elements into the chain are provided by disposing a cam follower 180 adjacent the cam wheel 160. The follower is attached to the end of an arm 182 which is pivoted at 181 by means of a screw threaded into a bracket 183 which is attached to bracket 74. The other end of the arm 182 is attached to link 176 by means of a pin 186 fixed to the arm and extending through a slot 184 in the link. Spring 185 is attached at one end to the pin 186 and at the other end to a fixed point 187 on the link 176 in order to hold the pin against the right hand end (Fig. 11) of the slot. This construction provides a yielding action between the arm 182 and link 176 so that movement of the arm to the left as indicated in the full line position, will pull link 176 through the spring. Another spring 188 is attached at one end to pin 186 and at the other to bracket 189 20 which supports the shaft 178 and associated finger mechanism. As the cam wheel 160 rotates, the follower rides upon the cam surfaces 164, being alternately pushed out by these surfaces and brought back again to the dot and dash line position by reason of spring 188 pulling the arm 182 back around its pivot. This rocks arm 182 and the action is transmitted through the linkage described to shaft 178 thus oscillating the finger 179 from the dot and dash line position of 25 Fig. 11 to the full line position. The heel of the finger is arranged to catch on the humps of the fastener elements. As the finger oscillates it pushes the elements positively and firmly in position into the continuously presented seats or 30 recesses in the chain.

The fastener elements supply mechanism consists of a drum 190 arranged to rotate on a shaft journalled in a suitable support 199. The drum is provided with an opening 192 in its end and carries fins 191 on its inner cylindrical surface. Extending through the opening and supported independently of the drum is provided a tube 194 to which is affixed a tray 193. The tube is provided with a longitudinal slot 195 along one side 45 of which are recesses 196. The slot is of a width slightly greater than the width or thickness of the fastener elements and the recesses 196 are of a size approximately equal to or slightly greater than the humps thereof. Adjacent the lower end of the tube 195 (Figs. 4 and 6) is provided a tripping device 200 which comprises a pair of plates between which an arcuate groove 201 is 50 constructed. At the mouth of the groove is provided an obstruction 202 arranged to obstruct further advance of the legs of the fastener elements as they travel down the slot 195. Connected to the lower end of the groove 201 is chute 30 to which is attached a bracket 203 connected by a flat spring 204 to a vibrating device 60 such as a rotating toothed wheel 206 operating against the roller 205 at the end of the spring. The vibrating device is set into operation and the drum 190 charged with fastener elements and rotated. Fins 191 raise elements and drop them on the tray 193 where some of them slide into groove 195 and are advanced down the tube by virtue of the inclination and vibration thereof. Unless the elements are disposed substantially as indicated in Fig. 5, they will drop out 65 of the tube when their humps reach recesses 196. If, however, they are disposed as shown in Fig. 5, they will ride down the slot and turn over into head first position by obstruction 202 in the manner shown in Fig. 6. The elements will then 70 75 80 85 90 95

be properly positioned to take up their downward course through the chute 30 and be fed into the chain as described.

A tripping mechanism (Figs. 1, 2 and 23) for throwing out the main clutch of the device in the event something goes wrong with the machine as for instance should a fastener element become accidentally wedged between moving parts, is operated by the collar 53 on the clutch member 49 as previously described. The tripping mechanism consists of an actuating arm 55 which supports rollers 54 disposed on each side of the collar or flange 53. Arm 55 is pivoted at 57 to the upstanding portion 56 of a bracket 69 which is fixed to the base plate 1. The arm has a foot portion 58 to which is pivotally connected a link 59 carrying lug 60. Supported on the bracket 69 is a spring operated plunger mechanism consisting of a housing 70 carrying a plunger 66 arranged to slide in bearing pieces 71 at the ends of the housing. On the plunger 66, inside the housing, is provided a spring 72 for pushing the plunger inwardly by virtue of the action of the spring against end piece 71 and collar 73 which is fixed on the plunger. Through the collar is extended a bar 64 extending through slot 65 in the housing. One end of a bar is adapted to contact with the upper end 63 of the bell crank 62 which is pivoted to the outside of the housing and which has a lower arm 61 terminating adjacent the lug 60. During the normal operation of the machine the spring is compressed by pulling back upon arm 64 and positioning bell crank 62 so that arm 63 holds the bar 64 against the tension of the spring. Upon the outer end of the plunger 66 is fixed a link 67 which connects the rod 68 and the plunger 66 together in fixed relation. The inner end of the plunger terminates adjacent the actuating arm 55 at 77 when the spring is compressed. Rod 68 connects to a large bell crank 78 (Fig. 3) which is pivoted underneath the base plate 1 at 79. The other end of the bell crank 80 (Figs. 3 and 25) is positioned adjacent the operating lever 26 so that movement of the former will actuate the latter.

The manner in which the main clutch is automatically thrown out is as follows: Suppose the machine is in operation and a fastener element becomes accidentally lodged between the chain and some fixed part of the machine. This immediately puts an abnormal load upon shaft 40 and the associated collar 49 which is keyed thereto, and the shaft 40 tends to stop. Power is continued to be applied through gears 46 and 47, however, with the result that the system breaks at the point at which it is designed to break, namely between clutch faces 49 and 50. The teeth of clutch face 50 commence to disengage and ride up on the teeth of the clutch face on collar 49, pushing the collar outwardly along its keyway against the action of the spring 51. This movement causes collar 53 to actuate arm 55 about its pivot in the direction shown by the arrow in Fig. 23. Through the mechanism described, bell crank 62 is turned so that the cammed surface of arm 63 moves downwardly and bar 64 is released to allow the plunger to move inwardly under the operation of the spring. The butt end of the plunger operates at 77 to further move arm 55 in the initial direction taken and collar 53 of the trip clutch is thus positively moved so that the clutch faces are out of contact. Through rod 68 the bell crank 78 is moved about its pivot causing arm 80 to push the operating

lever 26 outwardly as shown by the dot and dash lines in Fig. 25. As the operating lever 26 is normally (during operation) held down by depressing its catch portion 76 under the edge of the plate 1, movement of the arm 80 throws the catch portion out of engagement and allows the lever 26 to be elevated by reason of the action of spring 23 which exerts an upward push on the operating rod by virtue of its connection to rod 15 through treadle bar 25. Bars 15 and 25 are thus raised and the lever 13 elevated so that cam faces 16 are disposed in the path of keys 11 which by further rotation of the shaft 5 are driven inwardly along their keyways and out of contact with pin 18, thus releasing the clutch 15 and causing the machine to stop. The keys and cam faces are so arranged that the clutch will be disengaged just prior to or during the clamping operation of hammers 34, in order that the machine may be thrown out of gear before this action takes place.

Having thus described our invention, what we claim and desire to protect by Letters Patent is:

1. In an apparatus for setting legged elements on a carrying strip, in combination, means for spacing such elements astraddle such a strip, means for supplying said elements to said first means, means for clamping the legs of said elements on said strip and means for cutting off the supply of elements automatically on exhaustion of the strip supply.

2. In an apparatus for carrying legged elements, in combination, a chain having links between which the heads of said elements may be seated, supporting wheels for said chain, means for advancing said chain around said supporting wheels, means for seating separate elements between said links during said advance, and means associated with said last mentioned means to stop the supply of elements at predetermined times.

3. In an apparatus for setting legged elements on a carrying strip, in combination, a chain adapted to seat the heads of separate elements and continuously advance the same with legs straddling said strip, means for supplying elements into the seats in said chain, and means for clamping the legs of said elements upon said strip while the same is advanced by seated elements previously attached thereto.

4. In an apparatus for setting legged elements for slide-operable fasteners on a carrying strip, in combination, a chain adapted to seat the heads of separate elements and continuously advance the same with legs straddling said strip, means for supplying elements into the seats in said chain, and means for clamping the legs of said elements upon said strip, the carrying strip being moved by the chain and elements clamped thereon.

5. In an apparatus for setting legged elements for slide fasteners on a carrying strip, in combination, positive means for spacing such elements astraddle such a strip, means for supplying said elements to said first means and means of a shape to simultaneously engage the legs of a plurality of elements for successively clamping the legs of groups of said elements on said strip, whereby elements for slide-operable fasteners may be secured to the carrying strip.

6. In a separable fastener element setting machine, in combination, a series of continuously advancing pockets, means for supplying legged elements into said pockets with their legs outwardly extending and means for successively

clamping the legs of groups of said elements upon a carrying strip during said advance, whereby elements for slide-operable fasteners may be secured to the carrying strip.

5 7. In an apparatus for positioning legged elements, in combination, an endless chain having links between which the heads of said elements may be seated, means for continuously advancing said chain and means for seating separate elements between said links during said advance.

10 8. In an apparatus for setting legged elements on a carrying strip, in combination, an advancing chain, means for supplying said elements head first into said chain, and means for clamping the legs of the elements on a continuously advancing strip.

15 9. In an apparatus for setting legged elements on a carrying strip, in combination, a chain adapted to advance in parallelism with such a strip, means for supplying said elements into said chain with their legs protruding therefrom, and means for clamping the legs of the elements on said strip.

20 10. In combination with means for feeding legged elements astraddle a carrying strip and advancing the same continuously, means movable parallel to the direction of advance for clamping the legs of said elements upon said strip.

25 11. In combination with means for supplying and uniformly spacing legged elements astraddle a carrying strip and advancing said elements and strip continuously, means for clamping said elements in groups successively and the members 30 of each group simultaneously to the carrying strip in uniform spaced relation.

35 12. In combination with means for feeding legged elements astraddle a carrying strip and advancing the same continuously and without pause, reciprocating means for exerting a force only in a direction normal to the direction of said advance to clamp the legs upon said strip.

40 13. In combination with means for supplying legged elements astraddle a carrying strip and advancing the same continuously and without pause, means for simultaneously clamping the legs of a plurality of said elements to and around the edge of said strip during said advance.

45 14. In combination with means for supplying legged elements astraddle a carrying strip, means for successively clamping the legs of groups of elements upon said strip, whereby elements for slide-operable fasteners may be secured to the carrying strip.

50 15. The method of setting legged elements upon a carrying strip comprising arranging a plurality of said elements in a row in spaced parallel relation with their legs open and adjacent said strip and then successively clamping the legs of groups of said elements thereon in the same spaced parallel relation.

55 16. In an apparatus for positioning legged elements, in combination, a chain having links between which the heads of said elements may be seated, supporting wheels therefor, means for advancing said chain around said supporting wheels, and means for positively seating separate elements between said links during said advance, and while said links are out of alignment whereby seating said elements is facilitated.

60 17. In an apparatus for positioning legged elements, in combination, a chain having links between which the heads of groups of said elements may be seated, means for advancing said chain around said supporting wheels, and

means for seating separate elements between said links as they are opened out while advancing around one of the supporting wheels.

65 18. In combination with means for threading legged elements on to a carrying strip and advancing the same continuously, reciprocating means movable only in a direction normal to the direction of said advance while advancing with the strip to force said legs together upon said strip.

70 19. The method of setting legged elements upon a carrying strip comprising advancing and threading the legs of the elements about the edge of said strip and then clamping the legs on said strip by exerting a single force on said legs in a direction normal to the direction of travel of said elements and advancing the force while maintaining it in its normal direction during the advancing movement of the strip.

75 20. In a machine for securing legged elements on a flexible strip for slide-operable fasteners, in combination, open and closable means for receiving and holding elements with their legs accessible, means for supplying preformed elements to said open and closable means, means for initially positioning a flexible strip, means for guiding said flexible strip in a direction parallel and in proximity to a portion of the path of said open and closable means so as to position the strip between the legs of said elements, and means for 30 clamping the legs of said elements fast on the flexible strip.

80 21. In a machine for securing legged elements on a flexible strip for slide-operable fasteners, in combination, moving articulated means for receiving and maintaining said elements with their legs accessible, said articulated means being movable in a curved path for facilitating the reception of elements and in a straight path for facilitating the closing of the legs of said elements, 40 means for initially positioning a flexible strip, means for guiding the flexible strip in a path to have elements secured thereto, and means located adjacent the straight portion of the path of said articulated means for closing the legs of said 45 elements upon and securing them to the flexible strip without impairing movement of the articulated means.

85 22. In a machine for securing legged elements on a flexible strip for slide-operable fasteners, in combination, movable means for maintaining preformed legged elements in predetermined spaced relation and positioning said elements edgewise upon a flexible strip, a portion of the path of said movable means at least being straight, means 55 for introducing preformed legged elements into said first mentioned movable means in predetermined sequence, and means for successively securing said legged elements to and around the edge of said strip and at right angles thereto.

90 23. In a machine for securing legged elements on a flexible strip for slide-operable fasteners, in combination, endless articulated metallic means for receiving and holding a predetermined number of legged elements in uniformly spaced 60 parallel relation, means for sequentially supplying to said first mentioned means such legged elements with their leg portions accessible for closing, a source of flexible strip supply, and guiding means for conducting such flexible strip in a 70 predetermined path parallel to a portion of the path of said endless articulated metallic means, and means for securing the legs of said elements around an edge of said flexible strip at intervals.

95 24. In a machine for permanently affixing

legged elements of rigid material and for slide fasteners to a flexible support, an endless chain having links between which the heads of said elements are adapted to be seated, means for supplying said elements into seats intermediate said links at a rate greater than that induced by grav-

ity and at a point where the chain is bent to facilitate such seating of said elements.
